His Attorney.

UNITED STATES PATENT OFFICE.

CHARLES O. SHAVER, OF CHICAGO, ILLINOIS.

AUTOMOBILE-INDICATOR.

1,098,847.

Specification of Letters Patent.

Patented June 2, 1914.

Application filed April 9, 1913. Serial No. 759,890.

To all whom it may concern:

Be it known that I, CHARLES O. SHAVER, a citizen of the United States, and a resident of the city of Chicago, county of Cook, and State of Illinois, have invented certain new and useful Improvements in Automobile-Indicators, of which the following is a specification.

My invention relates to improvements in indicators and has for its object the production of a device which will indicate the license numbers of vehicles, and more particularly automobiles, and comprises means for adjusting a device, whereby the same will be adapted to display license numbers containing a large or small number of numerals.

The invention consists in the combinations and arrangements of parts hereinafter described and claimed.

The invention will be best understood by reference to the accompanying drawing forming a part of this specification, and in which—

Figure 1 is a perspective view of my improved indicator showing the number plates mounted therein, Fig. 2 is a cross-section of same, showing the illuminating lamp, and Fig. 3 is a longitudinal section of Fig. 1.

The preferred form of construction as illustrated in the drawing comprises two telescoping members 1 and 2 having closed outer ends 3 and 4 and curved reflector walls 5 and 6. The front sides of said members 1 and 2 are provided with alining openings substantially as indicated in the drawing. The longitudinal edges of member 1 along the opening therein are rebent forming slots or guides for the longitudinal edges of member 2 adjacent the opening in said member, see particularly Fig. 2. Guides 8 are secured on the inside of the upper and lower walls of said casing member 2 adjacent the opening thereof and extended beyond the open end of the latter into casing member 1 to a distance substantially as indicated in Fig. 3. Each guide 8 is formed with a base

9 and two perpendicular flanges 10 and 11 on said base providing a groove between such flanges for supporting the transparent plates 12 which carry the configurations comprising the sign or indicator. Said plates 12 are preferably formed of glass but any other suitable substance may be used and the configurations painted or otherwise secured thereon. The perforation 12' is

formed in end 4 of casing member 2 in registration with the grooves or slots in guides 8 and affords an opening through which plates 12 are entered and removed from the device. A rod 15 is inserted through perforations in casing member 2 and guides 8 forming a removable stop in guide members 8 for limiting the movement of plates 12 in this direction. A stop bar 14 is secured to the inner wall of the front side of member 1, adjacent the opening therein and serves with pin 15, on member 2, to prevent longitudinal movement of the plates 12 in the slots. An aperture is formed in the closed outer portion of tubular member 1 and a sheet of red glass 16 is mounted therein, in alinement with lamp 13, forming a tail light for the vehicle. Bosses 17 are mounted on the rear of said members 1 and 2 and have clamping screws 17 adapted for securing the respective members to the vehicle. It will thus be seen that in the above described construction, a plate of any desired length bearing one or all of the numbers, may be inserted in the indicator slots, or the requisite number of individual plates bearing designated indications, may be likewise inserted, and the members 1 and 2 adjusted longitudinally to hold the same compactly therein.

This device is particularly adaptable for use where the license numbers are changed yearly, affording means for increasing or decreasing the number of plates required to designate the said license number.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. An indicator consisting of a metallic body comprising adjustable reflecting members, having alining openings in corresponding faces thereof, one of said members being formed with slots and the other of said members having flanges and guide plates arranged thereon, said guide plates being formed with slots, the said flanges being adapted for slideable mounting in the first

22

5 named slots; a plurality of plates detachably mounted in the last named slots; and stops for preventing the longitudinal movement of said plates, substantially as described.

10 2. An indicator consisting of a metallic body comprising telescoping members, having alining openings in the front faces thereof, one of said members at said open portion being bent upwardly to form a slot, the other of said members at the open portion being formed with flanges, adapted for location in said first named slots; guide plates mounted in the last named member

15 and having slots arranged therein; a plurality of plates mounted in said guide slots; and stops arranged on said members adapted for holding the plates against longitudinal movement in said guide plates, substantially as described.

20

3. An indicator comprising two telescoping members having alining openings in corresponding faces thereof, one of said members having rebent portions along the longitudinal edges of its opening forming 25 guides and the longitudinal edges of the other member along its opening being slidably mounted in said guides; grooved guides carried by one of said members; stops adapted to extend between said grooved guides; and sign plates in said guides between said stops, substantially as described.

In testimony whereof I have signed my name to this specification in the presence of two subscribing witnesses.

CHARLES O. SHAVER.
